FIG. 1.

FIG. 2.

Inventor
William A. Moore,
By his Attorneys

Edgar Hale & Co.

UNITED STATES PATENT OFFICE.

WILLIAM A. MOORE, OF NEW YORK, N. Y.

SAFETY WINDOW-SEAT.

1,247,136.

Specification of Letters Patent. Patented Nov. 20, 1917.

Application filed June 26, 1917. Serial No. 177,052.

To all whom it may concern:

Be it known that I, WILLIAM A. MOORE, a citizen of the United States, and residing at New York, in the county of Bronx and

5 State of New York, have invented certain new and useful Improvements in Safety Window-Seats, of which the following is a specification, such as will enable those skilled in the art to which it appertains to 10 make and use the same.

This invention relates to window seats, chairs, or supports designed for use by window cleaners, and the object thereof is to provide an improved device of this class

15 which may be connected with a window frame and on which a window cleaner may sit or stand in the operation of cleaning a window; and with this and other objects in view the invention consists in a device of the 20 class specified constructed as hereinafter described and claimed.

The invention is fully disclosed in the following specification, of which the accompanying drawing forms a part, in which the 25 separate parts of my improvement are designated by suitable reference characters in each of the views, and in which:

Figure 1 is a sectional view of the bottom part of a window frame, showing my improved window seat or support, also in section;

Fig. 2 a plan view of the construction and attachment as shown in Fig. 1;

Fig. 3 a perspective view of the seat or 35 support detached; and,

Fig. 4 a section on the line 4—4 of Fig. 2.

In the drawing forming part of this specification, I have shown at a one side portion of a window frame and at a^2 the bottom or 40 bottom sill of said frame, said bottom or bottom sill being provided with the usual projecting ledge a^3 .

In the practice of my invention, I provide a window seat or support b which, in the 45 construction shown, is made of sheet metal bent at four different points b^2 , b^3 , b^4 and b^5 to form a box-shaped seat or base portion b^6 and a back portion b^7 , said back portion being double or composed of two parts riveted 50 together as shown at b^8 .

Across the top of the back portion b^7 and preferably at the back thereof is riveted, or otherwise secured, a cross bar c having projecting end portions c^2 with which are 55 loosely connected supplemental supports d , preferably of flexible material, and these

supplemental supports are provided at their free ends with hooks d^2 adapted to engage I-bolts or similar devices d^3 secured to, or in the sides a of the window frame. 60

I also provide rods e which are passed through the bottom box-shaped portion b^6 of the seat or support and are provided at their outer ends with heads e^2 and at their inner ends with nuts e^3 , and secured to the 65 bottom or sill of the window frame transversely thereof and outside of the spaces a^4 and a^5 in which the sashes are mounted are plates f having vertical ears f^2 .

In mounting the window seat or support 70 in connection with the window or window frame, the bottom or box-shaped portion b^6 of the seat or support is placed on the ledge a^3 of the window sill and said bottom or box-shaped portion abuts against a raised shoulder of the window sill at the bottom of the window as shown in Fig. 1, and the rods e are passed through the ears f^2 after which the nuts e^3 are applied and said rods together with the supplemental supports d securely hold the seat or support in connection with the window frame and a window cleaner may sit or stand on the seat or support with absolute security in the operation of cleaning the window or window sashes. 85

In the accompanying drawing, the lower sash g is shown but the upper sash is not shown, and it will be understood that the sashes may be raised and lowered in the usual manner. 90

Having fully described my invention, what I claim as new and desire to secure by Letters Patent, is:—

1. A window seat or support composed of a single sheet of metal bent to form a horizontal box-shaped bottom portion and an upright back portion. 95

2. A window seat or support composed of a single sheet of metal bent to form a horizontal box-shaped bottom portion and an 100 upright back portion composed of separate parts riveted together.

3. A window seat or support composed of sheet metal bent to form a box-shaped portion and an upright back portion, the box-shaped portion being provided with rods which pass inwardly therethrough and the inner ends of which are provided with means for detachably securing said rods to the bottom of the window frame and the top 110 of the back portion being provided with supplemental supports adapted to be detach-

ably connected with the sides of the window frame.

4. A window seat or support composed of a single sheet of metal bent to form a bottom box-shaped portion and an upright back portion, a cross bar secured to the top of the back portion and the ends of which extend beyond the sides of the back portion and are provided with apertures, rods passed inwardly through the bottom portion and detachably connected with the bottom of the window frame and flexible supporting de-

15 vices detachably connected with the apertures in the ends of said cross bar and with the sides of the window frame.

In testimony that I claim the foregoing as my invention I have signed my name in presence of the subscribing witnesses this 23rd day of June 1917.

WILLIAM A. MOORE.
